UNITED STATES PATENT OFFICE.

JOHN R. HARE, OF BALTIMORE, MARYLAND.

STREET-CAR FARE-BOX.

SPECIFICATION forming part of Letters Patent No. 274,319, dated March 20, 1883.

Application filed October 14, 1882. (No model.)

To all whom it may concern:

Be it known that I, JOHN R. HARE, of the city of Baltimore, and State of Maryland, have invented certain Improvements in Street-Car Fare-Boxes, of which the following is a specification.

The object of this invention is the construction of a car-fare box in which each fare or deposit is automatically separated from the others, in order that the driver can easily tell at any time whether or not the proper amounts or fares are deposited by the passengers.

The said invention consists in an inclosed box having an inwardly-opening swinging door for the deposit of fares, which is connected, by means of a rod or link and suitable ratchet mechanism, to a pair of rolls and an endless belt, the surface of which is provided with a series of projections which form pockets for isolating fares as deposited.

In the further description of my said invention which follows, reference is made to the accompanying drawings, forming a part hereof, and in which—

Figure I is a view of the box as seen from the interior of the car, with a portion of the casing of the box removed to show more fully the interior mechanism. Fig. II is a view of the invention with the outer covering removed, as seen from the exterior of the car. Fig. III is a vertical section of the box, taken on the dotted line *xy*, Fig. I. Fig. IV is a view of a part of the invention on an enlarged scale.

Similar letters of reference indicate similar parts in all the views.

A is a part of the front end of the car, and B a portion of the roof of the same.

C represents one of the forward car-windows.

D is the casing of the fare-box, which is preferably formed of wood and glass, glass plates being used in the front and rear of the box to allow the driver and passengers to see the fares deposited. The glass plates are represented by *a* in Fig. III.

E E' are revoluble drums, adapted to turn on axes *b*.

F is an endless belt or band, of rubber, cloth, leather, or other suitable material, placed

around the drums E. The outer surface of the band F has projections *c*, between which the fares, when deposited, are conducted. These projections, if the band is of rubber, may be cast or molded with it; but if the band is of other material the said projections can be easily attached. One of the drums, E, has a ratchet plate or disk, G, which, together with the said drum, is partially revolved at each opening of the fare-door H, the said door being connected to the ratchet-disk by means of a link or rod, *d*, lever *e*, and pawl *f*. Backward movement of the drums and ratchet-wheel, in the closing of the fare-door H, is prevented by means of a spring-pawl, I.

K and K' are plates to conduct fares, when deposited, to the pockets formed by the projections *c* on the band F.

L is a lamp for signaling purposes, and M a reflector to throw a portion of the light from the said lamp through the glass top of the box to the upper surface of the endless belt F. I do not claim, however, the reflector M or its combination with the lamp L.

Upon a passenger depositing his fare, whether the same consists of a coin, a number of coins, or a ticket, it is deflected by the plates K and K', the former of which is transparent, to one of the pockets of the endless band. Upon the passenger withdrawing his hand from the fare-opening, and the door being automatically closed, the pawl is moved to take another tooth of the ratchet, and the next fare, when deposited, reaches an unoccupied box or pocket, the first-named one being carried forward and to the space below the belt, which has a locked door.

I claim as my invention—

A car-fare box, which consists of the following essential elements in combination, viz: an inclosed casing having glass plates at the front and rear sides thereof, and an aperture in the rear side for the deposition of fares, a vertical inwardly-opening and gravitating swinging door hinged at its upper end and adapted to close the fare-aperture, a pair of revoluble drums surrounded by an endless belt or band having pockets on its outer surface, located below the said fare-aperture, ratchet mechanism to effect the movement of

the pocketed belt in one direction only, glass deflecting plates to guide the deposited fares to the endless pocketed belt, and a rod connecting the said swinging door with the said ratchet mechanism, whereby, in the movement of the said door in depositing a fare, the said endless belt is moved a distance equal to

the length of one of the fare-pockets, substantially as specified.

JOHN R. HARE.
